DESIGN FOR AN AIR PURIFYING CANISTER

William P. Yant and Kenneth B. Ray, Pittsburgh,
Pa., assignors to Mine Safety Appliances Com-
pany, Pittsburgh, Pa.

Application September 19, 1940, Serial No. 95,197
Term of patent 14 years

(Cl. D83—1)

To all whom it may concern:

Be it known that we, William P. Yant and Kenneth B. Ray, citizens of the United States, residing at Pittsburgh, in the county of Allegheny and State of Pennsylvania, have invented a new, original, and ornamental Design for Air Purifying Canister, of which the following is a specification, reference being had to the accompanying drawing, forming a part thereof.

Fig. 1 is a top plan view of an air purifying canister embodying our new design;

Fig. 2 is a side elevational view thereof, and Fig. 3 is a fragmentary end elevational view thereof with the lower portion of the canister broken away for convenience of illustration.

The dominant features of our design reside in the portions shown in full lines.

We claim:

The ornamental design for an air purifying canister, substantially as shown and described.

WILLIAM P. YANT.
KENNETH B. RAY.
